UNITED STATES PATENT OFFICE.

TIMOTHY J. McHUGH, OF CAMBRIDGE, MASSACHUSETTS, ASSIGNOR OF ONE-HALF TO WILLIAM H. GALLISON, OF BOSTON, MASSACHUSETTS.

DESIGN FOR A TRAP.

SPECIFICATION forming part of Design No. 27,535, dated August 17, 1897.

Application filed June 24, 1897. Serial No. 642,194. Term of patent 14 years.

To all whom it may concern:

Be it known that I, TIMOTHY J. McHUGH, of Cambridge, in the county of Middlesex and State of Massachusetts, have invented and produced a new and original Design for Traps, 5 of which the following is a specification, reference being had to the accompanying drawings, forming a part thereof.

Figure 1 is a side elevation of a trap, showing my new design. Fig. 2 is a front elevation of the same.

As shown on the drawings, the leading or material feature of my design consists of the circular body *a*, having the circular cap *b*, concentrically arranged with respect to the body *a*, the vertical pipe *c*, circular in cross-section, and the curved pipe *d*, also circular in cross-section.

In front view the trap presents the appearance of a circle with a radial extension, and 20 in side elevation it presents the general appearance of a **V** with one of its legs curved outward and the other curved inward and upward.

I claim—

The design for a trap substantially as shown and described.

In testimony whereof I have signed my name to this specification, in the presence of two subscribing witnesses, this 6th day of 30 May, A. D. 1897.

TIMOTHY J. McHUGH.

Witnesses:

A. D. HARRISON,
P. W. PEZZETTI.
